UNITED STATES PATENT OFFICE.

LUTHER F. SEELAR AND FRANKLIN G. NEAL, OF ST. LOUIS, MISSOURI, ASSIGNEES TO
ST. LOUIS CAR COMPANY, OF ST. LOUIS, MISSOURI, A CORPORATION OF MISSOURI.

DRIVING HORN.

Application filed May 15, 1922. Serial No. 561,200.

To all whom it may concern:

Be it known that we, LUTHER F. SEELAR and FRANKLIN G. NEAL, citizens of the United States, residing at St. Louis, State 5 of Missouri, have invented certain new and useful Improvements in Driving Horns, of which the following is a specification.

This invention relates to mountings for car bodies, and it comprises the combination 10 with a truck and body, of a block or casting secured to the truck, a block secured to the car frame and normally spaced a slight distance from said first block, said blocks being provided with engaging means in two 15 planes at right angles to each other to form a driving connection and to take up side play.

In the construction of driving horns by 20 which a car body is connected to the truck to transmit the driving power and control the side play of the car, it has heretofore been customary to provide a casting on the truck having a face adapted to be engaged by a face on the casting carried by the car 25 body to transmit driving power and braking action from the truck to the body. It has also been customary to provide a recess in the first block and a tongue carried by the second block adapted to enter said recess and 30 engage the side walls thereof when the car is turning a curve. The constructions heretofore employed in the art transmits this side motion to the car body as a jerk or sudden blow, causing the car to ride roughly.

In the present invention, there is provided 35 suitable springs or other cushioning means between the lateral faces which transmit side play to the car body, to break the shock of the sudden jerk caused by the direct engagement of the faces of the two castings, and thus more gradually transmit the motion from one unit to the other.

In the accompanying drawings, we have 40 shown several embodiments of the invention. In this showing:

Figure 1 is a side elevation of a truck and a portion of a car body showing the invention applied,

Figure 2 is a plan view of the mounting 45 in position,

Figure 3 is a vertical sectional view on line 3-3 of Figure 2,

Figure 4 is a plan view of a slightly modified form,

Figure 5 is a vertical sectional view on line 5-5 of Figure 4,

Figure 6 is a detail perspective view of the casting carried by the car frame,

Figure 7 is a side elevation of another form of the invention in applied position, 60

Figure 8 is a horizontal sectional view on line 8-8 of Figure 7,

Figure 9 is a vertical sectional view on line 9-9 of Figure 7,

Figure 10 is a front elevation, 65

Figure 11 is a detail view of the casting carried by the truck, and,

Figure 12 is a detail perspective view of the spring employed.

Referring to the drawings, the numeral 70 1 designates the car truck as a whole. The truck is provided with a clip 2, adapted to receive one end of a leaf spring 3, which is secured to a second clip 4, carried by the car frame. The spring mounting may be of 75 any desired type, although we prefer the spring mounting disclosed and claimed in the prior patent of Luther F. Seelar, No. 1,331,529, dated February 24, 1920.

In the form of the invention shown in 80 Figures 1 to 3 of the drawings, the driving connection between the car frame and the truck is provided by means of a casting 6, secured to the truck in any suitable manner, as at 7. This casting is substantially rectangular in shape, and is provided with a flat rear face 8. The side of the casting is further provided with a flat face 9.

The longitudinal beams of the car frame are designated at 10, and these beams are 90 provided with transverse connecting members in the form of channel irons 11, secured to the longitudinal beams in any suitable manner, as by plates 12. A substantially L-shaped casting 13 is secured to the transverse 95 channel irons 11, the casting being provided with an upper flange 14 to retain it in position and being secured to the channel iron in any suitable manner, as at 15. Opposite the channel iron, the casting is provided with 100 a flat face 16, which is adapted to contact with the flat face 8 of the truck casting. Referring to Figure 3 of the drawings, the outer end of the frame casting is provided with a flange 17, which, as shown, is formed 105 substantially cup-shaped provided with side walls 18. A pair of wear plates 19 are arranged on the open side of the cup-shaped

flange adapted to engage the face 9 of the other casting. These plates are provided with bolts or rods 20, extending through openings in the flange 17, and suitable 5 springs 21 are arranged between the flange 17 and the plates 19 to retain the plates in engagement with the face 9 of the other casting.

Referring to Figures 4 to 6 of the drawings, 10 the lateral engagement between the two castings in this form is obtained by means of a tongue 20 projecting from the casting 13. The casting is secured to the channel iron in any suitable manner, and is provided 15 with the upper retaining flange 14, as in the form of the invention previously described. The casting 6 is provided with a recess 21 forming a pair of spaced walls 22, the tongue 20 being received between the 20 walls. A spring 23 is carried by the tongue, being secured in a slot near the top of the tongue and retained in position by a rivet 24. The lower end of the spring is loosely mounted to permit it to move up and down 25 as the spring is compressed and expanded. As shown, a wear block 25 is secured to the tongue by a rivet 26, forming a slot 27 through which the end of the spring passes. The tongue is recessed, as at 28, for the 30 reception of the spring.

In Figures 7 to 12 of the drawings, the embodiment shown includes a casting 6 carried by the car truck and provided with a flat face 8, extending transversely of the car, 35 as in the other forms. The casting shown in this form of the drawings is provided with a rearwardly extending projection 29 to transmit side motion to the car body. Mounted on one of the transverse beams 40 of the car body and secured thereto in any suitable manner, there is provided a substantially L-shaped casting 30. The vertical leg 31 of the casting forms the driving and braking connection with the casting 6, 45 and a horizontal face 32 forms the transverse or lateral connection. As shown, the forward end of the casting is provided with a downwardly extending portion 33, forming a bearing for the reception of a pin 34. 50 One end of the pin is adapted to be inserted in an opening in the plate 31, the other end being reduced at 35 and adapted to be inserted in an opening in the flange 33. The filler block 36 may be arranged between the 55 plate 31 and the flange 33, being retained in position by suitable fastening means 37. A spring 38 is coiled about the pin 34 and is provided with a substantially horizontal arm 39 arranged adjacent to and spaced from 60 the horizontal face 32 of the casting. The position of the spring may be regulated by means of a threaded bolt 40, passing through an opening in the spring and provided with upper and lower nuts 41, and 42, for the 65 purpose of adjustment. The other end of

the spring extends downwardly, as at 43, between the plate 31 and the flat face 8 and in engagement with the projection 29 of the casting 6.

In the operation of the form shown in 70 Figures 1 to 3 of the drawings, the driving connection between the truck and the frame of the car is obtained by engagement between the faces 8 and 16 of the castings 6 and 13. In mounting a car frame upon a 75 truck, one set of the castings is arranged at the front and back of the truck on each side. When the car is being driven, the power applied to the truck moves the casting 6 upwardly to cause engagement between 80 the faces 8 and 16 of the castings at the rear of the truck and transmitting the power to the car frame. When the brakes of the car are applied, the set of castings at the front 85 of the car function to transmit the braking action to the car frame.

In rounding a curve, the wheels are first diverted from a straight line and this change in motion is carried into the car body through the castings. In the usual form of construction, the casting carried by the car truck suddenly engages the face of the casting carried by the car frame, which is slightly spaced therefrom, and causes a jerk in the car body. By means of springs 21, the plates 19 are 95 maintained in engagement with the face 9 of the casting 6, and the engagement of the castings, due to side motion, is thus cushioned, causing the body to turn more gradually and eliminating sudden jerks. 100

In the form of the invention shown in Figures 4 to 6 of the drawings, the driving power and braking action is transmitted in a similar manner. When the car enters a curve, the spring 23 cushions the engagement 105 between the tongue 20 and the side walls 22 of the casting 6, eliminating the usual sudden transmission of side motion from the truck to the frame of the car.

In the form of the invention shown in 110 Figures 7 to 12 of the drawings, the driving power and braking action is transmitted from the casting 6 to the casting 30, through the spring 38. When power is applied or the brakes set, the side of the spring moves 115 into engagement with the flat face 8 and transmits power or braking action to the leg 31 of the casting 30. In rounding a curve, the side play is transmitted from the projection 29 through the spring to the horizontal face 32 of the casting, cushioning the force exerted on the body of the car and gradually transmitting it from the car truck 120 to the car body.

It is to be understood that the forms of 125 our invention herewith shown and described are to be taken as preferred examples of the same, and that various changes in the shape, size, and arrangement of parts may be resorted to without departing from the 130

spirit of the invention or the scope of the subjoined claims.

Having thus described our invention, we claim:

- 5 1. The combination with a car truck and a car frame, of a driving connection comprising a casting secured to said truck, a second casting carried by the car frame, said castings being provided with engaging faces arranged transversely of the car to form a driving connection and being further provided with longitudinally arranged engaging portions to transmit side motion, and cushioning means arranged between said engaging portions.
- 10 2. A driving horn for trolley cars comprising a casting adapted to be secured to the car truck, a second casting secured to the frame, said castings being provided with engaging faces to form a driving connection, and spaced engaging portions at substantially right angles thereto, and cushioning means arranged between said spaced engaging portions.
- 15 3. A driving horn for trolley cars comprising a casting adapted to be secured to the car truck, a second casting secured to the frame, said castings being provided with engaging faces to form a driving connection, and engaging portions at substantially right angles thereto, and springs arranged between engaging portions.
- 20 4. A driving horn for trolley cars comprising a casting adapted to be secured to the car truck, a substantially L-shaped casting secured to the car frame and engaging two faces of the first casting, and cushioning means arranged between one arm of the L-

shaped casting and the engaging face of the first casting.

40

5. A driving horn for trolley cars comprising a casting secured to the car truck, a substantially L-shaped casting secured to the frame of the car, said castings being normally spaced from each other, but being adapted to engage due to relative movement of the truck and frame, the first casting being adapted to be engaged by each arm of the L-shaped casting for providing a driving connection and for transmitting side motion, and a plurality of coil springs arranged between the engaging faces arranged longitudinally of the car.

45

6. A driving horn for trolley cars comprising a casting adapted to be secured to the car truck, said casting being provided with a pair of flat faces arranged at substantially right angles to each other, a second casting secured to the car body, said casting being provided with a pair of flat faces at substantially right angles to each other, one of the faces of the first casting and one of the faces of the second casting being parallel to each other and normally spaced from each other, and a spring mounted on one of said castings and engaging the other two faces to transmit side play from the car truck to the car body.

50

In testimony whereof we affix our signatures in presence of two witnesses.
